REFLECTOR FOR SPOKED WHEELS

Henry Lindner, Wood Dale, Ill., assignor to Beatrice Foods Co., Chicago, Ill.

Filed Feb. 22, 1972, Ser. No. 228,476

Term of patent 14 years

Int. Cl. D29—02

U.S. Cl. D72—1 F

FIG. 1

FIG. 2

FIG. 5

FIG. 3

FIG. 4

FIG. 1 is a front perspective view of a reflector for spoked wheels showing my new design;

FIG. 2 is a front elevational view thereof;

FIG. 3 is a side elevational view thereof;

FIG. 4 is a rear elevational view thereof; and

FIG. 5 is an end elevational view thereof.

I claim:

The design for the reflector for spoked wheels, substantially as shown.
